HIRAM PERCY MAXIM, OF HARTFORD, CONNECTICUT.

AUTOMOBILE-STARTER.

1,020,106.

Specification of Letters Patent. Patented Mar. 12, 1912.

Application filed October 15, 1910. Serial No. 587,166.

To all whom it may concern:

Be it known that I, HIRAM PERCY MAXIM, a citizen of the United States, residing at Hartford, Connecticut, have made certain 5 new and useful Inventions Relating to Automobile-Starters, of which the following is a specification, taken in connection with the accompanying drawings, forming part of the same.

10 This invention relates especially to automobile starters in which the regular starting clutch on the gas engine shaft and the co-operating hand starting shaft and starting lever thereon are employed and may be 15 operated in the usual way without interfering with the auxiliary power starting devices.

A fluid pressure reservoir is preferably 20 provided with a needle valve shutoff and connected with one of the cylinders of the gas engine through a check valve so that during the normal operation of the engine, gas is forced into the reservoir and a pressure of several hundred pounds per square 25 inch maintained therein. A starter valve and cylinder pipe may be connected with this reservoir and with a starter cylinder so as to operate the toothed starter piston therein. The starter pinion meshing with 30 the teeth on the piston may be loosely mounted on the regular hand starting shaft and be provided with cam devices so that when it is first rotated on the admission of fluid pressure to the starter cylinder this pinion 35 and the hand starter shaft are moved longitudinally to cause the engagement of the usual starting clutch and thereupon start the engine during the further powerful rotation of the pinion. A cooling coil may 40 also be interposed in the connection adjacent the gas engine cylinder and a tire inflating valve and connection located adjacent this cooling coil.

In the accompanying drawing showing 45 in a somewhat diagrammatic way an illustrative embodiment of this invention, Figure 1 is a general elevation, Fig. 2 is a transverse section through the starting cylinder and connected parts taken substantially 50 along the line 2—2 of Fig. 3, Fig. 3 is a corresponding sectional view taken sub-

stantially along the axis of the hand starting shaft and Fig. 4 is a partial sectional plan view of the same.

In the illustrative embodiment of this 55 invention shown in the drawings the engine cylinders 1 may be mounted on the engine casing 2 as usual and one or more of these cylinders may be provided with a suitable connection 3 in which a cutoff valve 4 of any desired description may be mounted and connected with a suitable check valve 5 in which the ball check valve 55 is mounted so as to operate under these extreme service conditions in which it is exposed to high temperature engine gases and for this reason having the construction indicated which is shown in somewhat greater detail in the Maxim Patent No. 956,592 of 60 May 3, 1910. This check valve may communicate through suitable connections with the cooling coil 7 and reservoir 14, these connections comprising if desired a suitable pipe 6 communicating with the cooling coil of helical pipe or other construction and 65 having if desired in connection therewith a suitable tire valve 8 and handle 9 controlling the admission of the high pressure gases from the coil to a suitable tire inflating connection 10 by which the automobile tires 70 may be inflated when the engine is operated for this purpose in the manner indicated in said Maxim patent. A suitable spring or other check valve 11 may if desired be located in the connection 12 between the cooling coil and reservoir 14 and also it is desirable to have a positive reservoir shutoff valve closely adjacent the reservoir to positively hold the high pressure gases therein 75 for considerable periods as when the automobile is out of service for a considerable time. For this purpose a needle type valve such as indicated is desirable since it insures positive closure under such conditions. The reservoir may also be provided with a 80 suitable reservoir drain cock 45 of any desired construction to insure tight closure. The cylinder pipe 31 may connect the starter cylinder 16 with the reservoir and have located therein the starter valve 15 preferably 85 mounted on the dashboard of the machine or other convenient place to facilitate the 90 95 100

convenient operation of this starting device. This starter valve may as indicated be of the three-way type and have a suitable exhaust port 48 in the casing through which the gases in the starter cylinder may be allowed to exhaust.

As indicated in Figs. 2 and 3 the cylinder pipe 31 may be connected with the cylinder by a suitable coupling 41. The starter piston 28 may be mounted within this cylinder and be provided with suitable packing 29 of leather or other material held in position on the piston as by a suitable washer and retaining nut 32. The piston may also be provided with an internal aperture 35 to accommodate the piston spring 27 which normally tends to return this piston to its initial position indicated in Fig. 2. Suitable rack teeth 26 may be formed in the piston 20 and be given sufficient width to coöperate with the teeth on the pinion 24 as this pinion is moved longitudinally to some extent, these rack teeth also serving to hold the starter piston sufficiently in alinement to 25 secure efficient operation although other alining means may be employed if desired. The starter cylinder may be provided with a suitable cushioning relief hole 46 adjacent its forward end as indicated in Fig. 2 so 30 that as the piston advances to close this hole its further movement is cushioned by the fluid in this end 34 of the cylinder. A suitable cylinder drain cock 47 may also be provided to allow the escape of any liquid which 35 may collect in that end of the cylinder.

As indicated in Fig. 1, the engine shaft 22 may be provided with the usual clutch member 21 with which the coöperating starting clutch member 20 coöperates when the shaft 40 23 of the usual hand starting lever 19 is pushed inward sufficiently to bring these clutch members into engagement, the releasing spring 18 normally tending to hold these starting clutch members in the disengaged 45 position indicated.

The starter pinion 24 may as indicated in Figs. 3 and 4 be connected with or formed integral with a suitable pinion hub 38 and with a pinion sleeve 40 which may be loosely 50 mounted on the hand starting shaft 23 so that they may move longitudinally with respect thereto. The pinion sleeve 40 may, as indicated, project through a suitable guiding aperture in the head 17 of the pinion casing 43 which may as indicated in Fig. 2, be provided with suitable brackets by which it may be rigidly attached to the machine frame. The pinion hub 38 passes through a similar guiding aperture in the other head 60 of the casing which may as indicated in Fig. 3 be provided with a suitable annular recess 42 in which the pinion spring 25 may be located. This spring normally tends to force the pinion forward toward the starting clutch and controls its longitudinal

movement in connection with the pinion cam 36 secured to the pinion which coöperates with the disengaging cam 37 on the head 17 of the casing. This spring also insures the normal engagement of a clutch of any desired description provided between the pinion and starting clutch member 20 and this clutch may as indicated in Fig. 4 comprise one or more clutch projections such as 39 coöperating with corresponding recesses in the 75 clutch member 20.

It will thus be understood that the normal operation of the automobile engine maintains a high gas pressure of several hundred pounds per square inch in the reservoir 14 and when the starter valve 15 is operated this high pressure gas is admitted through the cylinder passage 30 so as to act upon the starting piston 28 and force it toward the left in Fig. 2 so as to correspondingly 80 rotate the pinion 24; the piston's motion being cushioned at the end of the stroke by the air held in the space 34 in the cylinder beyond the relief hole 46. The first twenty or twenty-five degrees of the pinion's rotation 85 sufficiently rotate the pinion cam 36 so that the pinion spring 25 can force the pinion and connected clutch member 20 longitudinally into engagement with the coöperating member 21 of the starting clutch so that 90 the subsequent sixty-five or seventy degrees of movement of the pinion are communicated to the engine shaft 22 and connected parts so as to give a powerful starting impulse to the engine. When the engine starts 95 it serves to disengage the starting clutch in the usual way and in case of back firing of the engine the pinion cam 36 disengages this clutch before the starting piston has reached the beginning of its stroke. Of course, when the engine has started the operator brings the starter valve 15 back to its initial position indicated in Fig. 1 and the gases in the starter cylinder are discharged 100 through the exhaust port 48 while the starter piston is moved back to its initial position shown in Fig. 2 by the piston spring 27. This power starting device does not in any way interfere with the regular operation of the hand starting mechanism since the hand starting shaft 23 may be forced longitudinally inward by the lever 19, thus forcing the starting clutch members into engagement and simultaneously carrying the clutch member 20 out of engagement with the clutch 110 projections 39 on the pinion sleeve shown in Figs. 3 and 4.

Having described this invention in connection with illustrative embodiments, proportions, and arrangements of parts, to the 115 details of which disclosure the invention is not of course to be limited, what is claimed as new and what is desired to be secured by Letters Patent is set forth in the appended 120 claims.

1. In automobile starters, a gas engine comprising an engine shaft, starting clutch, hand starting shaft and connected hand starting lever normally disengaged from said engine shaft, a ball check valve and cut-off valve connected to one of the cylinders of said engine, a reservoir provided with a needle valve reservoir shutoff and a connection between said check valve and said reservoir shutoff valve comprising an auxiliary check valve, a cooling coil in said connection, a tire valve and tire inflating connection adjacent said cooling coil, a cylinder pipe and three-way starter valve communicating with said connection adjacent said reservoir, a starter cylinder having a relief hole and a cylinder drain cock and connected to said cylinder pipe, a starter piston provided with wide rack teeth and with a piston aperture mounted within said cylinder, a piston spring in said piston aperture to normally return said piston to initial position, a starter pinion meshing with said rack teeth and having a connected pinion sleeve and hub loosely mounted on said hand starting shaft to allow the normal operation of said starting lever, a pinion clutch normally in engagement with the adjacent member of said starting clutch, a pinion cam secured to said pinion, a co-operating stationary disengaging cam and a pinion spring tending to hold said pinion cam in engagement and cause the engagement of said starting clutch when said pinion is first rotated by fluid pressure from said reservoir on operating said starter valve to thereupon start said engine.

2. In automobile starters, a gas engine comprising an engine shaft, starting clutch, hand starting shaft and connected starting lever normally disengaged from said engine shaft, a check valve connected to one of the cylinders of said engine, a reservoir provided with a reservoir shutoff valve and a connection between said check valve and said reservoir shutoff valve comprising a cooling coil, a cylinder pipe and starter valve communicating with said connection adjacent said reservoir, a starter cylinder having cushioning means and connected with said cylinder pipe, a starter piston provided with rack teeth and means to normally return said piston to initial position, a starter pinion meshing with said rack teeth and having a connected pinion sleeve loosely mounted on said hand starting shaft to allow the normal operation of the connected hand starting lever, a pinion clutch connected with said pinion and normally in engagement with the adjacent member of said starting clutch, a pinion cam secured to said pinion, a co-operating stationary disengaging cam and a pinion spring tending to hold said pinion cam in engagement and cause the engagement of said starting clutch

when said pinion is first rotated by fluid from said reservoir to thereupon start said engine.

3. In automobile starters, a gas engine comprising an engine shaft, starting clutch, hand starting shaft and connected hand starting lever normally disengaged from said engine shaft, a reservoir provided with a reservoir shutoff valve, a connection comprising a check valve between said reservoir shutoff valve and one of the cylinders of said gas engine, a cylinder pipe and starter valve communicating with said connection between said check valve and said reservoir, a starter cylinder connected to said cylinder pipe, a starter piston provided with rack teeth and having a connected pinion sleeve mounted on said hand starting shaft to allow the normal operation of said hand starting lever and means co-operating with said pinion to cause the engagement of said starting clutch when said pinion is first rotated by fluid from said reservoir to thereupon start said engine.

4. In automobile starters, a gas engine comprising an engine shaft, a starting clutch, hand starting shaft and connected hand starting lever normally disengaged from said engine shaft, a reservoir, a connection comprising a check valve between said reservoir and one of the cylinders of said gas engine, a cylinder pipe and starter valve communicating with said connection between said reservoir and said check valve, a starter cylinder connected to said cylinder pipe, a starter piston within said cylinder, a starter member and connected sleeve operatively connected with said piston and mounted on said hand starting shaft to allow the normal operation of said starting lever and means co-operating with said starter member to cause the engagement of said starting clutch when said member is first operated by fluid from said reservoir to thereupon start said engine.

5. In automobile starters, an engine comprising an engine shaft, starting clutch and hand starting lever normally disengaged from said engine shaft, a reservoir, a connection comprising a check valve between said reservoir and one of the cylinders of said engine, a cylinder pipe and starter valve communicating with said connection between said reservoir and said check valve, a starter cylinder connected with said cylinder pipe, a starter piston provided with rack teeth mounted within said cylinder, means to normally return said piston to initial position, a starter pinion meshing with said rack teeth and having a connected pinion sleeve mounted to co-operate with said engine shaft and allow the normal operation of said hand starting lever and means to connect said starter pinion with said engine shaft when said pinion is first

rotated by fluid from said reservoir to thereupon start said engine.

6. In automobile starters, an engine comprising an engine shaft and hand starting lever normally disengaged from said engine shaft, a reservoir, a connection comprising a check valve between said reservoir and one of the cylinders of said engine, a cylinder pipe and starter valve communicating with said reservoir, a starter cylinder connected to said cylinder pipe, a starter piston mounted within said cylinder, a starter member operatively connected with said starter piston and co-operating with said engine shaft and means to operatively connect said starter member with said engine shaft when said starter member is first rotated by fluid from said reservoir to thereupon start said engine.

7. In automobile starters, an engine comprising an engine shaft and hand starting lever normally disengaged from said engine shaft, a reservoir, a connection between said reservoir and said engine to produce fluid pressure in said reservoir during the operation of said engine, starter devices co-operating with said engine shaft and allowing the normal operation of said hand starting lever, a starter valve connected with said reservoir and with said starter devices to operate the same by fluid pressure from said reservoir and means to connect said starter devices with said engine shaft when said starter devices are first operated by fluid pressure from said reservoir to thereupon start said engine.

8. In automobile starters, an engine comprising an engine shaft, a hand starting lever mounted in coöperation with but normally disengaged from said engine shaft, a reservoir, a connection between said reservoir and said engine to normally create fluid pressure in said reservoir during the operation of said engine, starter devices coöperating with but normally disengaged from said engine shaft and allowing the normal operation of said hand starting lever independent of said starter devices in manually starting said engine, a starter valve between said reservoir and said starter devices and means to connect said starter devices with said engine shaft when said starter devices are first operated by fluid pressure from said reservoir to thereupon start said engine.

9. In automobile starters, an engine shaft, a starting clutch, hand starting shaft and hand starting lever normally disengaged from said engine shaft, a fluid pressure reservoir, a cylinder pipe and starter valve communicating with said reservoir, a starter cylinder connected to said cylinder pipe, a starter piston provided with rack teeth mounted within said cylinder, means to normally return said piston to initial po-

sition, a starter pinion meshing with said teeth and having a connected pinion sleeve loosely mounted on said hand starting shaft to allow the normal operation of said hand starting lever and means to cause the engagement of said starting clutch when said starting pinion is first rotated by fluid pressure from said reservoir to thereupon start said engine. 70

10. In automobile starters, an engine comprising an engine shaft, starting clutch, hand starting shaft and hand starting lever normally disengaged from said engine shaft, a fluid pressure reservoir, a cylinder pipe and starter valve communicating with said reservoir, a starter cylinder connected to said cylinder pipe, a starter piston provided with rack teeth mounted within said cylinder, means to normally return said piston to initial position, a starter pinion meshing with said rack teeth and having a connected pinion sleeve mounted on said hand starting shaft to allow the normal operation of said hand starting lever, a pinion cam secured to said starter pinion and co-operating means to cause the engagement of said starting clutch when said starter pinion is first rotated by fluid pressure from said reservoir to thereupon rotate said engine shaft and start said engine. 95

11. In engine starters, a hand starting shaft, a starter cylinder having a cushioning relief aperture, a starter pinion provided with rack teeth mounted within said cylinder, a piston spring normally returning said piston to initial position, a starter pinion meshing with said rack teeth and having a connected sleeve loosely mounted on said hand starting shaft to allow its normal operation, a pinion cam secured to said pinion and cooperating means to longitudinally move said starting pinion and hand starting shaft when said pinion is first rotated. 100 105

12. In engine starters, a starting shaft, a starter cylinder, a starter piston having rack teeth mounted within said cylinder, a starter pinion meshing with said rack teeth and having a connected pinion sleeve loosely mounted on said starting shaft to allow its normal operation, a pinion cam secured to said starter pinion, a coöperating stationary disengaging cam and a pinion spring tending to hold said pinion cam in engagement and normally longitudinally move said pinion and starting shaft when said pinion is first rotated. 110 115 120

13. In engine starters, a starting shaft, a starter cylinder, a starter piston mounted within said cylinder and having connected rack teeth, a starter pinion meshing with said rack teeth and mounted adjacent said starting shaft to allow its normal operation, a pinion cam coöoperating with said starter pinion, a coöperating stationary disengaging cam and a pinion spring tending 125
130

- to hold said pinion cam in engagement and longitudinally move said pinion and starting shaft when said pinion is rotated.
14. In engine starters, an engine comprising an engine shaft and hand starting lever mounted in coöperation with but normally disengaged from said engine shaft, a reservoir, a cylinder pipe and starter valve communicating with said reservoir, a starter cylinder connected to said cylinder pipe, a starter piston mounted within said cylinder, a starter member operatively connected with said starter piston and coöperating with said engine shaft and means including a cam on said starter member to operatively connect said starter member with said engine shaft when said starter member is rotated by fluid from said reservoir to thereupon start said engine.
15. In engine starters, an engine comprising an engine shaft and hand starting lever mounted in coöperation with but normally disengaged from said engine shaft, a reservoir, a connection between said reservoir and said engine to normally create fluid pressure in said reservoir during the operation of said engine, starter devices coöperating with but disengaged from said engine shaft during the normal operation of said engine and allowing the normal operation of said hand starting lever independent of said starter devices in manually starting said engine, a starter valve between said reservoir and said starter devices and means to connect said starter devices with said engine shaft when said starter devices are operated by fluid from said reservoir to thereupon start said engine.
16. In gas engine starters, an engine comprising an engine shaft, a hand starting lever mounted in coöperation with but normally disengaged from said engine shaft, a reservoir and starter valve communicating with said reservoir, starter devices coöperating with but normally disengaged from said engine shaft and allowing the normal operation of said hand starting lever independent of said starter devices in manually starting said engine, means to connect said starter devices with said engine shaft when said starter devices are operated by fluid from said reservoir to thereupon start said engine and means to disconnect said starter devices from said engine shaft in case of back firing of said engine.
17. In gas engine starters, an engine comprising an engine shaft, an independently operating hand starting lever normally disengaged from said engine shaft, a reservoir, a cylinder pipe and starter valve communicating with said reservoir, a starter cylinder connected to said cylinder pipe, a starter piston mounted within said cylinder, a starter member, operatively connected with said starter piston and coöperating with

- said engine shaft, means to operatively connect said starter member with said engine shaft when said starter member is operated by gaseous fluid from said reservoir to thereupon start said engine and means to disconnect said starter member from said engine shaft in case of back firing of said engine.
18. In gas engine starters, an engine comprising an engine shaft, a reservoir, a cylinder pipe and starter valve communicating with said reservoir, a starter cylinder connected to said cylinder pipe, a starter piston mounted within said cylinder, means to normally return said piston to its initial position adjacent the end of said cylinder, a starter member operatively connected with said starter piston and coöperating with said engine shaft, means to operatively connect said starter member with said engine shaft when said starter member is operated by fluid from said reservoir to thereupon start said engine and means to disconnect said starter member from said engine shaft in case of back firing of said engine.
19. In gas engine starters, an engine comprising an engine shaft, a reservoir, a cylinder pipe and starter valve communicating with said reservoir, a starter cylinder connected to said cylinder pipe, a starter piston mounted within said cylinder, means to normally return said piston to its initial position adjacent the end of said cylinder, a starter member operatively connected with said starter piston and coöperating with said engine shaft and means to operatively connect said starter member with said engine shaft when said starter member is first operated by fluid from said reservoir to thereupon start said engine.
20. In gas engine starters, an engine comprising an engine shaft, a reservoir, a connection between said reservoir and a cylinder of said engine to normally create gaseous fluid pressure in said reservoir during the operation of said engine, starter devices coöperating with but normally disengaged from said engine shaft, a starter valve between said reservoir and said starter devices, means to connect said starter devices with said engine shaft when said starter devices are first operated by fluid from said reservoir to thereupon start said engine and means to disconnect said starter devices from said engine shaft in case of back firing of said engine.
21. In gas engine starters, an engine comprising an engine shaft, a hand starting lever mounted in coöperation with but normally disengaged from said engine shaft, a reservoir, a connection between said reservoir and one of the cylinders of said engine to normally create fluid pressure in said reservoir during the operation of said engine, starter devices coöperating with but normally disengaged from said engine shaft

and allowing the normal operation of said hand starting lever independent of said starter devices in manually starting said engine, a starter valve between said reservoir and said starter devices, means to connect said starter devices with said engine shaft when said starter devices are operated by fluid pressure from said reservoir to there-

upon start said engine and means to disconnect said starter devices from said engine shaft in case of back firing of said engine.
